UNITED STATES PATENT OFFICE.

GEORGE D. BURTON, OF NEW IPSWICH, NEW HAMPSHIRE.

ELECTRICAL TRAIN-SIGNAL.

SPECIFICATION forming part of Letters Patent No. 426,522, dated April 29, 1890.

Application filed November 22, 1887. Serial No. 255,853. (No model.)

To all whom it may concern:

Be it known that I, GEORGE D. BURTON, of New Ipswich, in the county of Hillsborough and State of New Hampshire, have invented 5 a new and useful Improvement in Electrical Train-Signals, of which the following, taken in connection with the accompanying drawings, is a specification.

My invention relates to an electric signaling system for railway-trains, whereby both the engineer and conductor of a moving train are enabled to communicate with each other at will by a predetermined code of electric signals transmitted in either direction over a 15 line-circuit by the alternate make and break of said circuit.

The particular object of my invention is to provide such an arrangement of circuits, electrical connections, and auxiliary apparatus 20 as will render it feasible and practicable for the conductor to signal to the engineer from any coach or car of the train which he may occupy at the time when he desires to give such signal, and to enable the engineer to transmit 25 significant signals back to the conductor, no matter in which car the latter person may be. For the attainment of these several objects my invention embraces the following essential 30 co-operating features: first, an arrangement of circuits enveloped by and operating through a single bell-cord, which passes throughout the train and serves as a circuit-controller for said signaling-circuits; second, a novel construction of electrical coupling, 35 comprising a connecting-plug and a receptacle for the said plug, containing switching and circuit-controlling devices, whereby the electrical continuity of the circuits is preserved or interrupted between any two adjacent cars of the train, and, third, certain electrical connections, annunciating apparatus, and other details of construction and combination of parts, more fully described hereinafter, and particularly pointed out in the appended 40 claims.

In the accompanying drawings I have shown certain appliances for adequately carrying out my invention. However, I desire it to be distinctly understood that I do not confine 45 myself strictly to the construction and arrangements illustrated, since obvious departures may be made therefrom without deviat-

ing from the scope of my invention as covered by the claims hereto annexed.

Referring to the drawings, Figure 1 is a side 55 elevation of a railway-train, comprising one car, a tender, and engine, equipped with my improved train-signaling devices. Fig. 2 is a vertical central sectional view of the adjustable electrical coupling-plug and its receptacle containing the circuit-controlling mechanism. Fig. 3 is a front end elevation of Fig. 2. Fig. 4 is a detail longitudinal sectional view of the connecting-plug shown in position in Fig. 2, with this difference, however, that the 60 line on which said section is taken passes diametrically through a different plane for the purpose of showing certain parts hereinafter described. Fig. 5 is a detail transverse vertical section taken on the line $x-x$ of Fig. 2. 70 Fig. 6 is a view similar to Fig. 2, the only difference being that this illustration shows the relative arrangement of the receptacle for the electrical coupling-plug which would be attached to the other end of the cord L, secured 75 to the plug K K' in Fig. 2, and the circuit-switching devices N N' N'', &c., being omitted. Fig. 7 is a diagrammatical view of the 80 circuits and connections throughout the train.

Like letters of reference indicate like or corresponding parts in the several views of the drawings.

Referring to the drawings by letter, A, B, and C respectively indicate the passenger-coach, tender, and engine, comprising a railway-train, all of any approved construction, therefore requiring no further description herein, except for those particular parts which co-operate with my invention.

Referring to Fig. 1, the passenger-coach A 90 is provided at each end with a boxing E or E', containing the parts hereinafter described and so fitted through a suitable rectangular slot in each end portion of said coach as to be accessible from the interior or exterior thereof, 95 as will be readily perceived by an inspection of the figure.

L L respectively designate two flexible cords having at each extremity a conducting-plug K, permanently secured thereto and 100 containing three insulated conducting-wires, which terminate in electrical contact with three independent conducting-plates attached to the exterior surface of each plug. (See

Figs. 2, 4, and 6.) Between any two adjacent cars a cord L, having the before-mentioned plugs K K at each extremity, connects the boxings E or E' at the adjacent ends of the 5 respective cars with each other for the obvious purpose of connecting the circuits of one car with those of the car next adjacent. Each boxing E or E' is made in two parts e e', which are respectively mortised out, as 10 shown, for the purpose of accommodating the interior parts, and are made of insulating material, preferably wood.

Substantially in the center of the end of the 15 boxing E or E' (which projects exteriorly through the end partition of its respective car) is formed a circular opening for permitting the free insertion of the forward portion of a plug K.

D² and H² respectively indicate two laterally-projecting blocks secured to and insulated from the side of the portion e' of the boxing and each having a curved spring contact plate D' or H' secured thereto. Each 20 spring contact plate D' or H' consists of a longitudinal curved contact-plate and a central metallic conducting portion, and each plate D' or H' is attached centrally to its respective block D² H², with both of its free extremities curving outwardly and upwardly, 25 thereby forming an inwardly-tapering or conical longitudinal recess for the reception of the correspondingly-tapering or conical forward portion of the respective plug K, which is designed to enter said recess and engage the plates D' H'. 30

By reference to Fig. 2 it will be seen that the blocks D² H² and their attached spring contact plates D' H' are arranged in the same vertical plane, so that when the plug K 40 is inserted in the position shown in said figure the respective plates D' H' engage the exterior surface of the plug K at diametrically-opposite points; but in a different vertical plane from the plates D' H' is arranged 45 the vertical downwardly-dependant spring contact finger z², secured to a laterally-projecting offset of the portion e of the boxing by a suitable screw at its upper end and having its forward lower free extremity curving 50 inwardly toward the adjacent surface of the plug K. (See Fig. 6.)

N designates a lever pivoted by the small stud or arbor N' to the side of the boxing and having the laterally-projecting contact-pins N² N³ secured thereto at equidistant 55 points from its fulcrum and arranged in the same vertical line.

N⁴ is an insulated disk, which is rigidly keyed to the pivot N', and is provided with 60 two arc-shaped recesses or slots N⁶, which correspond in shape and relative situation to those of the contact-pins N² N³, which latter pass through said slots N⁶, and are capable of a limited play or reciprocation therein, as will 65 be clearly understood from the operation hereinafter given.

The lower extremity of the lever N is pro-

vided with an eye N⁵, through which is passed the bell-cord M, which in turn is secured therein by the ligature M', and passes through 70 the interior of the coach A in the ordinary manner and is similarly connected to a lever N at the rear extremity of said coach.

S indicates a coiled retractile spring attached at one extremity to the lever N and at 75 its other end to the boxing E or E' and serves to restore the lever to its normal position, as shown in Fig. 2, after displacement, and to keep the contact-pins N² N³ normally out of engagement with the rearwardly-extending 80 ends of the respective spring contact plates D' H', which project across the face of the disk N⁴ in proximity to their respective contact-pins N² N³, so that when the said lever N is shifted from its normal inactive position 85 the said contact-pins will simultaneously engage and make electrical contact with their respective spring-plates D' H'.

Referring to Fig. 3, K² K³ respectively represent two clamping-lever arms hinged together in any suitable manner, as at K⁸, and each provided with the outwardly-curved portions y' y², which conform to the contour of the neck of a plug K, whereby the said plug may be securely embraced and fastened in 90 its seat or socket when inserted by the lever-arms K² K³, which latter are held together in a closed position by the spring-hasp K⁷, secured transversely over the lower ends of said arms and arranged to exert a frictional bearing or tension thereupon sufficient to prevent the jar or concussion of the train from displacing or loosening their closed position. Each plug K consists of a forward-tapering conical portion K', a neck y⁴, and a rear 95 spherical handle y⁵. The main body of the plug is made of wood or hard rubber and is provided with a longitudinal central circular perforation running from the end of the handle y⁵, through the neck y⁴, up into the beginning of the tapering forward portion K', where the said perforation branches into three smaller diverging apertures, each of which latter leads to one of the conducting-plates d h z⁸ on the exterior surface of the plug 105 K. In the first-mentioned perforation of the plug is permanently fastened one extremity of the connecting-cord L, which envelops the three independent insulated circuit-wires D, 110 z, and H, which latter, instead of terminating abruptly with the end of said cord, continue through their respective diverging branch passages or leads, and finally terminate in electrical contact with the several conducting-plates d, h, and z⁸. The forward conical 115 portion k' of the plug is faced at diametrically-opposite points with the current-conducting terminal plates d h, both of which are designed to rest in electrical contact with the 120 spring-plates D' H' when the plug K is inserted in the position shown in Fig. 2. At substantially right angles to the vertical plane in which the plates d h are arranged is placed a similar current-conducting terminal-plate 125

130

z^8 , (see Figs. 4 and 5,) which in turn is intended to make electrical contact with the spring-finger z^2 when the plug is placed in its proper position.

5 Referring now more particularly to Fig. 7, the engine C is equipped with an annunciating-bell T, a battery Q, in circuit with said bell, and the two circuit-controlling switches z^6 and P. A boxing E or E' is placed at some 10 convenient overhead point, such as V, in said engine, and is similar in construction and arrangement to the respective boxings E or E' in the coach A, except the switching-lever N, and its auxiliary parts are needless, and 15 therefore are omitted. A cord L, of the construction previously described, connects the boxing on the engine with the forward boxing on the coach A, which latter boxing is connected by the bell-cord M with the rear boxing, as before described. In the coach A is 20 located an annunciator z^{10} , included in a closed branch or shunt circuit from the bell-cord M.

The electrical connections and circuits throughout the train here shown are as follows: The path of the circuit whereby the conductor can signal from the coach A to the engineer in engine C may be traced as follows: from one pole of the battery Q through the spring contact plate H' of the boxing at 25 V, the adjacent terminal plate h of the plug k, the wire H, passing through the cord L, the corresponding terminal plate h of the plug K at the other extremity of said cord, and the spring contact plate H' of the boxing E. 30 Here the path is broken by the rear extremity of the plate H' being out of contact with the contact-pin N^3 ; but should the conductor in the car A pull the cord M the lever N would be shifted to the position shown in 35 dotted lines in Fig. 2 and the contact-pins N^2 N^3 would be simultaneously brought in contact with the plates D' H'. Thus the path of the circuit would continue by the pin N^3 of boxing E, the lever N, contact-pin N^2 , 40 spring-plate D', contact-plate d of boxing E, return-wire D of cord L, contact-plate d of boxing at V, spring-plate D', wire h^4 , switch P, through the annunciator T, and wire h^9 to the other pole of the battery Q. Thus it will 45 be seen that if the conductor in the coach A should pull the bell-cord and the switch P is closed the circuit would be closed by the lever N of boxing E, and thereby ringing the bell or annunciator in the cab of the engine, 50 the circuit through the annunciator z^{10} in the coach A being open. If, on the other hand, the engineer desired to signal back to the conductor, he would merely adjust the switch z^6 so as to close the circuit from the battery 55 Q through the annunciator z^{10} of the car A. Then in this instance the path of the current would be as follows: from one pole of the battery Q, by wire z^7 , switch z^6 , wire z^5 , contact-finger z^3 , plate z^8 , wire z of the cord L, to 60 contact-plate z^8 of boxing E, contact-finger z^2 , wire z of the loop W, and bell-cord M, and other loop W, to the contact-finger z^2 of the

boxing E', plate z^8 , wire z of second cord L, and similarly on throughout the train until it reaches the last boxing E or E' of the car, 70 where the wire z is looped into the wire D of the bell-cord in any suitable manner. Then the path continues back by second cord L, wire H, plate h, and spring-plate h' of boxing E', wire h of loop W, and cord M in coach A, 75 branch wire d^5 , annunciator z^{10} , branch z^9 , and back by wire D', &c., to the wire d^4 and the other pole of the battery Q. Thus, by aid of the shunt consisting of the wire z , the plate z^8 , finger z^2 , and branches z^9 and d^5 , the 80 annunciators throughout the train are simultaneously operated, notwithstanding the other signaling-circuit is open at every lever N; or, in other words, the wires H and z and their auxiliary connections form the car annunciating-circuit, the said annunciators being connected in multiple arc, while the wires D and H, with the shifting-lever and auxiliary contacts, form the engine signaling circuit. Finally, if the conductor were in the coach (not 85 shown) in the rear of A, and he should be 90 desirous of signaling the engineer, he would likewise pull the cord M in that particular coach, and the annunciator in the engine would be operated without ringing the bells 95 through the intervening coaches.

For the sake of convenience we will suppose that another car intervenes between the engine and the car A. Then, in accordance with the preceding statement, the path of the 100 current would be the same as that described when the cord M was pulled in the car A, except that the path of the current would be shunted around the switching-lever N and contact-pins N^2 N^3 by the loop-cord W and its 105 inclosed wires D and H, which latter are respectively in electrical contact with the plates D' and H' of the boxing E or E', thereby forming a metallic circuit throughout the train, which is open only in the last coach by the 110 lever N not being in the position shown in Fig. 2. Thus it will be seen that the conductor's annunciating-circuit has its electrical 115 continuity preserved throughout the whole train, except in the last car, where it may be closed, in a manner previously described, by the pull of the bell-cord M, and that in all the 120 intermediate coaches a simple shunt or branch of the main circuit adapted to be similarly operated by the pull of the bell-cord is provided.

The engineer's signaling-circuit is formed by a third wire shunted in the main circuit, continuing through the train, and is looped into one leg or side of the other circuit in the 125 last coach, so that the same is only open at the engineer's circuit-controller, and the annunciators in the several cars are looped in multiple arc in the engineer's signaling-circuit.

Another and simpler description of the arrangement of the two independent circuits would be to say that the main signaling-circuit for the conductor was open only at the 130

rear of the car, and that the path of the current from the battery Q could be short-circuited in all the intermediate cars, while the engineer's signaling-circuit was open only in the engine and a third wire was looped into one leg or branch of the conductor's circuit to form a closed metallic line throughout the train.

It will be obvious that any suitable or available source of electrical energy may be used, and that the circuit-controllers, annunciators, switches, and electrical connections may be of any approved or desired construction, without departing from the spirit of my invention.

Having thus fully and accurately described my invention, what I claim, and desire to secure by Letters Patent, is—

1. For train-signaling, the combination, with three co-extensive conductors extending throughout the train, inclosed in a cord and forming two distinct electrical circuits, the one for establishing communication from conductor to engineer and the other for establishing communication from engineer to conductor, with circuit-controllers each of which has a pivoted lever, the cord inclosing the wires acting as bell or pull cord for operating said levers, as set forth.
2. Three conductors extending the whole length of the train through suitable coupling-switches forming two independent electrical circuits supplied by one common source of electricity, one of the circuits comprising a bell in each car of the train and a controlling-switch in the engineer's cab and the other a bell in the cab, and contact devices in each car comprising a pivoted lever, and a bell-cord formed of the inclosed circuit-wires, as set forth.
3. The combination, with an insertible plug having surface-contact plates in circuit with electrical conductors, of a receptacle containing spring contact plates arranged to be engaged by a dual set of contacts and in circuit with electrical conductors, a set of

pin-contacts in circuit with each other and arranged to simultaneously and severally engage said spring-contacts, and a pivoted lever for jointly moving said pin-contacts, substantially as specified.

4. The combination, with an insertible plug having surface-contact plates in circuit with electrical conductors, of a receptacle having spring contact plates arranged to be engaged by a dual set of contacts and in circuit with electrical conductors, a set of pin-contacts in circuit with each other and arranged to simultaneously and severally engage said spring-contacts, a pivoted lever for jointly moving said pin-contacts, and a cord containing electric conductors for operating said lever, substantially as specified.

5. In combination, three circuit-wires inclosed in a cord, spring contact plates in circuit with said wires, a plug having surface-contacts to engage said spring contact plates and having independent circuit-wires passing through it, and a pivoted lever for operating the spring-contacts, the cord containing the three circuit-wires being attached to said lever and serving as a bell cord or pull for operating it, as set forth.

6. In combination, the pivoted arm N, carrying contact-pins N'' N''', the spring for holding said arm and pins in a normally-inactive position, the cord M serving as a bell or pull cord to bring said parts into active position, the three wires enveloped by said cord, the spring-contacts, and the plug carrying contact-plates to engage said spring-contacts and complete the circuit when the lever is operated by pulling cord M, as set forth.

In testimony whereof I have signed my name to this specification, in the presence of two subscribing witnesses, on this 10th day of November, A. D. 1887.
